Fig. 3

UNITED STATES PATENT OFFICE.

JOHN WRIGHT WARREN, OF ELIZABETHTON, TENNESSEE.

TILE-MOLDING MACHINE.

Application filed June 11, 1923. Serial No. 644,661.

This invention relates to improvements in tile molding machines of the type adapted to form shingle tiles, and the primary object of the invention is to furnish a simple and inexpensive machine capable of rapidly producing concrete shingle tiles.

Another object of the invention is to provide a tile molding machine adapted to provide ribs on and recesses in the tile in order to form a tile of maximum strength and minimum weight.

A further object of the invention is to provide a tile forming machine adapted to place an end lug on the tile for the purpose of cutting off capillary action and thus preventing leakage in the roof where said tiles are employed.

Another object is to furnish pallets which shape the bottom of each tile and provide it with cones or lugs which form depressions in the tile to facilitate the passage of a nail through the latter without fracturing the tile. These depressions do not extend entirely through the tile so that perforations will only be provided at the points necessary to receive the nails. The arrangement of these cones on the pallet is such as to form the depressions at the points in the tile where they may be needed, when the tile is cut or divided to fit the hips and valleys of a roof. The pallets are also provided with depressions for the purpose of forming lugs on the underside of the tile, one of the lugs being adapted to engage a cleat on a roof.

In the accompanying drawing, a preferred embodiment of the invention is illustrated, and attention is called to the fact that the details illustrated may be changed without departing from the spirit of the invention as expressed in the claims. For the purpose of the present description, reference will be had to the drawings, in which:

Figure 1 is a side view of the improved machine.

Fig. 2 is a top plan.

Fig. 3 is a rear view.

Fig. 4 is a vertical longitudinal sectional view of a portion of the machine, showing the plastic material forming the tile arranged in the mold box on the pallet, and the edge cutter in engagement with the upper edge of the mold box.

Fig. 5 is a transverse vertical sectional view of a portion of the machine and illus-

trating the manner in which the trowel bar scrapes surplus material from the upper surface of the plastic mass.

Fig. 6 is a top plan view of the improved pallet.

Fig. 7 is a side view; and

Fig. 8 is an end view respective of the same.

The general construction of the present machine is well known, and the present invention resides in the mold box, pallet, trowel bar and edge cutter.

The machine consists of a frame 1 of any desired construction provided at its upper end with horizontally disposed cross-bars 2 secured in position by means of bolts 3. A mold box 4 is secured to the bars 2 by any suitable means and ejector pins 5 project into the box. These ejector pins have their lower ends connected to a plate 6 which is vertically reciprocated by a rod 7 connected to a bell-crank treadle 8 that is pivotally supported at 9. When the operator steps on the treadle 8, the pins 5 will be raised in a manner which is obvious.

The mold box 4 is of special construction and it consists of side walls 10 and 11, and end walls 12 and 13. The side walls have their upper edges arranged in the same horizontal plane, as shown in Fig. 5, but the end walls have edges of special configuration. As shown in Fig. 3, each end wall has an angular recess 14 which merges into one end of a horizontal surface 15. The opposite end of the surface 15 merges into the side wall of a groove 16 and the opposite wall of this groove merges into a horizontal surface 17 that is arranged in the same horizontal plane as the surface 18 of the recess 14. One corner of the box, as best shown in Fig. 2 is provided with an inwardly extending angular lug 19 which joins the walls 11 and 13 and is adapted to form an angular recess in one corner of a rectangular tile molding in said machine. This special shape of the mold box is provided for other purposes which will be hereinafter described.

The pallet 20 which also forms a novel feature of the present invention is removably arranged in the mold box and it preferably consists of a cast metal plate adapted to rest upon the upper ends of the adjusting screws 5^a which project from cross-

bars 2 and are adjustable to produce the desired thickness of tile. This pallet has an upper surface of novel design in order to shape the underside of the tile to be 5 molded in the box. This upper surface is provided near one side edge 21 with a horizontal surface 22 that extends from one end edge 23 of the pallet to a substantially vertical wall 24 spaced from the opposite 10 site end edge 25 of the pallet. The surface 22 merges into a longitudinally extending upright rib 26 which reaches from the edge 23 to the wall 24. The corner of the pallet between the wall 24 and the 15 edge 25 forms a lug 27, which is arranged in a lower plane than the upper surface of the rib 26. This lug 27 together with the upright wall 24 is adapted to form a depending lug at one corner of a tile, which 20 will fit in an opposite cut out corner of the tile formed by the lug 19 of the mold box. The pallet is provided with a horizontal ledge 28 at one end which extends from a cut out corner 29 of the pallet across 25 the lug 27 to the edge 21 of the pallet. The main upper surface 30 of the pallet is in a horizontal plane and rectangular raised portions 31 extend upwardly from this surface. Conical pins or lugs 32 also extend 30 upwardly from the surface 30 and are designed to form depressions in the underside of the tile made by the machine. These lugs 32 are in substantially T-shaped formation, so that they form the depressions 35 in the tile at proper points to be utilized even when the tile is divided to fit a certain spot in a roof. The lugs 32 do not extend entirely through the material of which the tile is formed, but terminate a short distance from the upper surface of 40 the tile, and this permits the operator to drive a nail through the tile at the points where the depressions occur, and the hole thus made may be utilized for driving a nail through the tile to secure the same to 45 a roof. The cone shape of the depressions formed in the tile will facilitate the passage of a nail through the tile without fracturing the latter. One end of the pallet 50 is also provided with a ledge 33 designed to form a depending lug at one end of the cast tile.

When using the machine, this special pallet is placed in the box on the screws 55 5^a and then the plastic material 34 to be molded is placed in the box. As shown in Fig. 4, the ledge 28 of the pallet will form a transverse lug 35 at one end of tile, while the ledge 33 will form a similar lug 36 at 60 the opposite end of the tile. At the same time the surface 30 and raised portions 31 of the pallet will form cavities 37 and ribs 38 in the underside of the tile.

Referring to Fig. 5, it will be noted that 65 the horizontal surface 30 at one edge of the walls, each of which has a straight unbroken

pallet will form a ledge 39 at one edge of the tile material 34, while the surfaces 22 and 70 30, and the rib 26 of the pallet are forming a hook portion 40 at the opposite edge of the tile.

In order to shape the upper surface of the tile, the improved trowel bar 41 has been devised. This bar has handles 42 at its opposite ends to permit the operator to move the bar over the mold box, while the bar is sliding on guide rails 43. The trowel bar has an elongated recess 44 in its under side and adjacent to one end of this recess it has a depending lug 45 which shapes the upper edge at one side of the tile. It will be noted 80 from Fig. 5 that the lug 26 of the pallet provides a downwardly extending hook at one side edge portion of the tile while the lug 45 of the trowel bar forms an upwardly extending hook at the opposite edge portion 85 of the tile. In the finished tiles, these hooks of adjacent tiles are adapted to interlock.

From Fig. 3 it may be seen that the upper edge of each of the end walls 12 and 13 of the mold box is similar in shape to the lower edge of the intermediate portion of the trowel bar 41, so that said trowel bar may be slid over the box without interference. In this movement the corner 46 of the trowel bar will move through the cut out corner 14 of the mold box, while the lug 45 of the trowel bar will pass through the cavity 16 of the mold box.

After the trowel bar has been moved over the mold box, the cutter 47 is operated, and this cutter has a corner lug conforming to the corner lug 19 of the mold box. The lower edge of the cutter 47 conforms generally to the shape of the upper edges of the walls of the mold box, so that said cutter 105 functions to cut surplus material from the edge of the tile.

After the treadle 8 has been depressed to raise ejector pins 5 and the finished tile has been removed and placed in rack for curing, 110 the cutter is raised to the position shown in Figs. 1, 2 and 3.

The adjusting screws 5^a permit raising or lowering of the pallet to produce tiles of the desired thickness.

It is believed from the foregoing, that the construction and operation of the machine may be readily understood, and it is apparent that the elements disclosed may be changed without departing from the spirit 120 of the invention as claimed.

What is claimed and desired to be secured by Letters Patent is:

1. A molding machine including a mold box provided at one corner only with an inwardly extending angular lug, a rectangular pallet arranged in said box and having an angular notch at one corner adapted to engage said lug, said mold box having end 125 walls, each of which has a straight unbroken

upper edge provided at one end with an angular notch and at its opposite end with a channel-shaped portion, a trowel bar adapted to slide over said box and having an under surface conforming to the shape of the upper edge of each end of the box for smoothing and shaping the upper surface of a tile in the box, and a pivotally mounted endless, rectangular cutter conforming in shape to the upper edge of the box and adapted to snugly engage said edge for cutting surplus material from the edge of the tile when the pallet is raised, said pallet being provided with spaced upwardly extending conical lugs of less height than the upper edges of the end walls of the box and adapted to form depressions in the underside of the tile of less height than the thickness of the latter, said lugs being in T-shaped formation with the stem of the T extending

substantially throughout the length of the pallet.

2. A molding machine including a mold box, a pallet arranged in said box and having upwardly extending rectangular lugs 25 arranged at opposite sides of a longitudinally disposed central channel, a longitudinal series of spaced conical lugs extending upwardly from the bottom of said channel and of less height than the upper edges of 30 the end walls of the box, and a trowel bar mounted for movement over said box and provided with an under surface conforming to the shape of the upper edges of the end walls of the box for shaping the upper surface of a tile within the box while the pallet is shaping the underside of the tile.

In testimony whereof I affix my signature.

JOHN WRIGHT WARREN.
